UNITED STATES PATENT OFFICE

2,664,851

DEVICE FOR APPLYING ADHESIVE SUBSTANCES TO TAPELIKE ARTICLES

Elmer A. Hillard, Bristol, Tenn.

Application April 11, 1952, Serial No. 281,848

3 Claims. (Cl. 118—12)

1

This invention relates to a device for applying a relatively viscous, liquid substance such as water solvent or plastic resin adhesives, to articles such as braids, fringes, and the like.

More specifically, the invention has reference to a hand or bench tool particularly adapted for use in the upholstering trade, for the purpose of applying glue or other forms of liquid adhesives to various furniture trimmings such as "gimp," braids, fringes, and other tape-like articles that are to be secured adhesively to a furniture piece.

At present, adhesive substances are applied to articles of the character described by hand, in the art to which the invention relates, and commonly, brushes, paddles, and other types of conventional applicators are used.

It will be readily appreciated that the conventional method employed, for applying adhesive substances to braids or fringes is tedious and time consuming, and accordingly, the broad object of the present invention is to provide a device which will facilitate measurably the application of a selected adhesive to articles of the type stated.

I believe it to be worthy of observation, in this regard, that the mere provision of an applicator that will coat an adhesive substance upon flexible objects of the character referred to would not, in and of itself, adapt the applicator for use in the upholsterer's trade. This is due to the fact that the adhesives used in this trade in many instances are adversely affected by exposure to air, and excessive exposure of the adhesive to the atmosphere tends to dry and thicken the adhesive substance so as to reduce considerably its ready usability.

Therefore, an important object of the present invention is to provide an applicator of the type stated novelly designed in a manner to reduce to a minimum the surface area of the substance that will be exposed to the damaging action of the atmosphere, the device constituting the present invention being provided with a valved reservoir which can be sealed off completely when the device is not in use, and being further provided with a well from which the adhesive substance is drawn during use, with the well being so constructed as to reduce to a minimum the area of the adhesive exposed to air.

Yet another object of the present invention is to provide, in a device of the character referred to, an article-coating means in the form of a rotatable wheel, which will be rotated by the article drawn thereover, a novel, adjustable guide means being associated with the wheel in

2

such a manner as to releasably hold the article to be coated in engagement with the periphery of the wheel.

Yet another object is to provide a device as described wherein the rotatable wheel, its associated guide means, and a wheel support assembly will be formed as a single unit capable of being removed bodily from the well of the device, thus to facilitate cleaning of the parts, said cleaning being a necessity when highly tacky, quick drying adhesive substances are used.

Still another important object is to provide, in association with the removable wheel support assembly, a valve assembly that controls the sealing of the reservoir, which valve assembly will be so associated with the wheel support assembly as to cause the wheel support assembly to be engaged within the well of the device whenever the valve is open, and to be adapted for removal from the well whenever the valve is closed.

A still further important object is to provide, in an applicator as described, a construction wherein the reservoir, well, wheel support assembly, and the control means for adjusting the guide and valve, will all be so designed and related to one another as to permit the tool to be used either as a bench tool or one that can be manually grasped.

Yet another object is to provide a construction, in a tool as stated, wherein the parts noted in the paragraph immediately above will be so related as to be capable of being grasped with facility during the actual operation of coating an article with an adhesive substance.

Other objects will appear from the following description, the claims appended thereto, and from the annexed drawing, in which like reference characters designate like parts throughout the several views, and wherein:

Figure 1 is a top plan view of a tool formed in accordance with the present invention;

Figure 2 is a side elevational view;

Figure 3 is a side elevational view in which the side opposite that shown in Figure 2 is illustrated;

Figure 4 is a longitudinal sectional view taken substantially on line 4—4 of Figure 1;

Figure 5 is an end elevational view, taken from the left of Figure 2;

Figure 6 is a transverse sectional view taken on line 6—6 of Figure 2; and

Figure 7 is a transverse sectional view through the valve assembly, taken on line 7—7 of Figure 4.

In the drawings, there has been illustrated a res-

ervoir 10 which is of elongated, tubular formation, thus to provide a handle which can be grasped in one hand of a user. At its outer end, the reservoir is externally threaded for attachment thereto of a removable cap 12, and it will be understood that whenever it is desired to charge the reservoir with a quantity of an adhesive substance, the cap 12 is removed.

At its other end, the reservoir 10 is formed with an inner end wall 14, in which there is 10 formed an air vent opening 16 disposed above and aligned vertically with a relatively large fluid flow opening 18.

A plurality of laterally projected lugs 20 are formed upon the inner end of the reservoir 10, said lugs being apertured for extension therethrough of connecting screws 22. The screws 22 serve to secure a valve block 24 fixedly but removably to the inner end of the reservoir, said valve block being of rectangular cross sectional configuration (Figure 7) and having openings 28 at the several corners thereof through which the screws 22 extend. The screws, after extending through the valve block, are threadedly engaged in the inner end of a well designated generally by the reference numeral 28.

For the purpose of preventing leakage between the opposite sides of the valve block and the reservoir and the well respectively, gaskets 30 are employed.

Formed in the valve block is a flow passage 32 shaped cross sectionally like and registering with the fluid flow opening 18, and spaced vertically of and above the flow passage is an air passage 34 registering with the air vent opening 16.

A tapered valve seat 38 is also formed in the valve block, the passages 32, 34 communicating with opposite sides of said valve seat, as best shown in Figure 4.

A valve 36 is of tapered, plug-like formation, and is rotatably mounted in the valve seat 38, said valve having an air passage 40 disposed above a flow passage 42. In the open position of the valve 36, the passages 40, 42 are adapted to provide communication between the reservoir and the well. However, when the valve is rotated through 90 degrees of a circle, communication between the reservoir and well will be closed off completely, so as to seal the reservoir, and thus prevent the reserve quantity of adhesive disposed therein from being affected adversely by exposure to the atmosphere.

By reason of the construction so far illustrated and described, it may be noted that ordinarily the adhesive contained within the reservoir 10 is protected against exposure to the atmosphere. However, when the device is to be used and the valve is open, the adhesive within the reservoir will gravitate to the interior of the well 28 through the registering fluid flow passages of the reservoir, valve, and well. As adhesive pours into the well, air will enter the reservoir through the registering air passages, so as to assure the continued flowing of adhesive from the reservoir to the well during the regular use of the device.

Means is provided for manually operating the valve 36, and to this end, the valve is integrally formed, at its upper end, with a non-circular valve stem 44 having an axial, threaded socket. A valve handle 46 has an opening receiving the stem 44, a screw 48 being threaded into the socket of the stem for the purpose of securing the handle to the valve.

As may be noted from Figure 1, the valve handle 46 is formed, at its inner end, with a

laterally projected lock member 49 which, in the open position of the valve will project longitudinally of the device into the space above the well 28. In the closed position of the valve, the lock member 49 will be shifted out of its position above the well.

Means is provided for holding the valve 36 firmly seated within the valve block, said means including a screw 50 threaded into the lower end of the valve, a spring 52 being circumscribed about said screw and being held under compression between the head of the screw and a washer 54 that engages the underside of the valve block.

Considering the construction of the well 28, as will be noted from Figures 1 and 6, the well includes parallel, upstanding side walls 56, said walls being integral with an inner end wall 58. The inner end wall 58 is formed with apertures 60, 62 registering with the passages 32, 34 of the valve block.

The well 28 also is formed integrally with an inner bottom wall portion 64, that merges, intermediate the opposite ends of the well, into an arcuate outer end wall 66, formed at its upper end with an inturned, rounded lip 68.

The particular formation of the well is adapted to reduce to a minimum the amount of surface area of the adhesive that will be exposed to atmosphere during the use of the device. It is for this purpose that the well is rounded at its outer end, the arcuate configuration of the end wall 66 being adapted to cooperate with an applicator wheel, that is mounted in the well and which will be described hereinafter, for the purpose of reducing to a minimum the exposed surface area of the adhesive within the well.

The curved construction of the wall 66 of the well further is adapted to permit closer contact of the device with the trimming that is being applied to an article of furniture, at the beginning of the operation of coating the trimming and applying it to the article of furniture.

The rounded lip 68 also has a specific purpose, said lip serving as a front hold-down for the wheel support assembly 69 of the device.

The wheel support assembly 69 is a self-contained unit adapted to be removed bodily from the well 28 after each use of the tool, and includes a pair of transversely spaced, upstanding side plates 70, 72, that are adapted to be disposed in close proximity to the respective side walls 56 of the well in the inserted position of the assembly 69.

The side plates 70, 72 are fixedly connected in spaced relation by connecting pins 74 (Figures 4 and 6), said pins being formed at one end with reduced, threaded extensions 76 threadable into correspondingly threaded recesses provided in the side plate 72. At their other ends, the pins 74 are formed with axial, threaded recesses receiving screws 78 that extend through the side plate 70.

Mounted for rotation between the respective side plates is an applicator wheel 80, said wheel extending downwardly within the well and being thus adapted to be partially immersed in an adhesive substance disposed within the well, for coating of the periphery of the wheel during use of the tool. Any suitable rotative mounting of the wheel can be employed, and as one example of such a mounting, I show the wheel as being mounted upon a medially splined axle 82 shouldered adjacent its opposite ends, and having reduced ends extending into suitable bearing openings provided in the respective side plates.

For the purpose of applying a desirably thin, uniform coating of adhesive to the periphery of

the wheel, gauge plates 84, 86 are employed (Figure 1), said gauge plates being mounted upon the top edge of the side plate 70. The gauge plate 84 is formed with spaced, aligned slots 88, receiving screws 90 that are threadable into the side plate 70, thus to permit the plate 84 to be adjustably positioned relative to the periphery of the wheel, thereby to permit a coating of a selected thickness to be applied to the wheel during rotation thereof. The gauge plate 86 is provided with similar slots, and is similarly secured to the side plate 70.

Formed upon the plates 84, 86 respectively are lateral extensions 92, 94, said extensions being disposed transversely of the wheel and having beveled edges arranged in close proximity to the wheel surface (Figure 4). The extensions, as will be appreciated, will be shifted toward and away from the surface of the wheel when the adjustments in the gauge plates are made.

The gauge plates are not secured to the side plate 72, but the side plate 72 is formed with a longitudinal slot 96 (Figure 5), that extends along the inner surface thereof, and receives the free side edges of the extensions 92, 94 of the gauge plates.

The gauge plate 86, as will be noted from Figure 1, is provided with a rearwardly directed projection 98, that will underlie and be engaged by the lock member 49 of the handle 46, in the open valve position. By reason of this construction, the valve handle 46 is adapted to retain the entire wheel assembly within the well 28, said handle cooperating with the lip 68 in this regard, in a manner best shown in Figure 4. When, however, the valve handle 46 is partially rotated for the purpose of closing the valve, the lock member 49 will be shifted out of engagement with the projection 98, and will permit the entire wheel assembly to be removed bodily from the well, to facilitate the cleaning of said assembly and well.

It is also worthy of note, as shown in Figure 1, that the projection 98 is relatively narrow, so as to provide open spaces 100 at either side thereof. This is for the purpose of permitting a user to dip a brush or small paddle into the well, if, for example, a braid or other piece of trim is being applied in close quarters into which the tool cannot be extended.

Mounted for up and down sliding movement, in a plane normal to the axis of rotation of the wheel 80, is a flat guide plate 102, said guide plate being disposed in close proximity to one face of the wheel. The guide plate 102 is provided, at opposite ends thereof, with guide pins 104, said pins extending transversely of the wheel and being spaced circumferentially of the wheel, as best shown in Figure 4. The guide pins, when the guide plate 102 is shifted toward the axis of the wheel, will engage a piece of braid, trim, or other tape-like object, and will force said object into engagement with the periphery of the wheel. Thus, by pulling the object longitudinally of the tool, the wheel will be rotated by said object, and the object will thus be coated with the adhesive picked up by the wheel during rotation thereof.

A slide 106 is secured to the outer surface of the guide plate 102, intermediate the opposite ends of the guide plate. This slide is grooved vertically at its opposite ends, for slidable engagement with the confronting, spaced edges of upstanding extensions 108 formed integrally upon the side plate 72. Screws 107 (Figure 2) are employed to secure the guide plate to the slide.

The guide plate is normally urged in a direction away from the axis of rotation of the wheel,

and this will be effective to normally dispose the guide pins 104 in an inoperative position in which they will be spaced substantially away from the periphery of the wheel 80. A spring 110 is employed to urge the guide plate to said inoperative position, said spring seating in a recess formed in the underside of the slide 106, and in a recess formed in the side plate 72, as best shown in Figure 6.

Manually operated means is provided, however, for urging the guide plate and its associated guide pins 104 into an operative position, against the pressure of the spring, and to this end, there is utilized a link 112 (Figure 3) pivotally connected by a screw 114 to the slide 106, and by a screw 116 to a control handle 118. As will be noted, the control handle 118 is pivotally connected as at 120, at one end of the control handle, to one of the upstanding extensions 108.

It will thus be noted that when the handle 118 is swung upwardly, the guide pins 104 will be adjusted to their inoperative position, movement of the guide pins to their operative, lower position being effected by downward swinging movement 25 of the handle 118.

The handle 118, as will be seen, is of arcuate formation, the handle having a straight intermediate portion and having a downwardly offset free end portion 122 that is extended laterally over 30 the reservoir 10 (Figure 1) to provide a thumb rest.

The device, when used as a hand tool, is used as follows. First, the trimming to be glued is unrolled from a spool thereof, to a desired length. 35 With the device set conveniently upon a work bench or the like, and with the guide pins 104 disposed in their inoperative position, a few inches of the trimming is passed across the wheel to pick off some of the adhesive.

40 This portion of the trimming is then applied to the beginning point of the work, running toward the operator. The device is then grasped in one hand, the reservoir providing a handle and the thumb rest being conveniently positioned for depression by the thumb of said hand. The other hand of the user is now disposed to hold the trimming clear of the work. The guides 104 will now hold the trimming against the wheel 80, and the trimming can be applied to the work throughout 45 its length, with adhesive being applied thereto due to rotation of the wheel by the trimming during the application of said trimming to the work.

When the operation is completed, the user need merely rotate the valve handle to the valve closing position thereof, and this will permit the wheel assembly to be removed bodily from the well. The valve is then opened momentarily, and the device tilted to permit the adhesive left in the well to flow back into the reservoir. The valve 55 is then closed, so as to seal the reservoir.

If water solvent adhesive is being used, the entire device can be dropped into a container of water, awaiting its next use, it being understood in this connection that the device would be constructed wholly from non-corrosive materials. If, however, plastic resin adhesives are being used, the separated parts of the device would be cleaned in an appropriate solvent, and then rinsed off in water.

70 It is believed apparent that the invention is not necessarily confined to the specific use or uses thereof described above, since it may be utilized for any purpose to which it may be suited. Nor is the invention to be necessarily limited to the specific construction illustrated and described,

since such construction is only intended to be illustrative of the principles of operation and the means presently devised to carry out said principles, it being considered that the invention comprehends any minor change in construction that may be permitted within the scope of the appended claims.

What is claimed is:

1. A device for coating an adhesive substance upon tape-like articles, comprising: a well adapted as a container for an adhesive substance; a wheel support assembly removably mounted in said well and including fixedly connected, spaced side plates; an applicator wheel rotatably mounted on and between the side plates in position to be partially immersed in said substance, for coating of the periphery of the wheel with the adhesive substance responsive to rotation of the wheel; a guide plate disposed adjacent one face of the wheel and supported upon one of the side plates for sliding movement in a plane normal to the axis of rotation of the wheel; a spring held under compression between the guide plate and said one side plate tensioned to normally urge the guide plate away from said axis; a control handle pivotally connected to said one side plate and operatively connected with the guide plate to shift the same toward said axis against the pressure of the spring; and guide pins affixed to the guide plate in close proximity to the wheel and spaced circumferentially of the wheel in parallelism with said axis, said guide pins being shiftable, responsive to sliding movement of the guide plate, toward and away from the wheel to operative and inoperative positions respectively and being arranged, when adjusted toward the wheel, for guiding of an article to be coated into engagement with said periphery, thereby to effect rotation of the wheel and coating of the article responsive to movement of said article in the direction of its length while in the wheel engaging position thereof.

2. A device for coating an adhesive substance upon tape-like articles, comprising: a reservoir adapted to hold an adhesive substance and shaped as a handle; a well secured to one end of and communicating with the reservoir for flow of said substance into the well from the reservoir; a wheel support assembly removably mounted in said well and including fixedly connected, spaced side plates; an applicator wheel rotatably mounted on and between the side plates in position to be partially immersed in said substance, for coating of the periphery of the wheel with the substance responsive to rotation of the wheel; a guide plate disposed adjacent one face of the wheel and supported on one of the side plates for sliding movement in a plane normal to the axis of rotation of the wheel; a spring held under compression between the guide plate and said one side plate tensioned to normally urge the guide plate away from said axis; a control handle pivotally connected to said one side plate and operatively connected with the guide plate to shift the same toward said axis against the pressure of the spring; and guide pins affixed to the guide plate in close proximity to the wheel and spaced circumferentially of the wheel in parallelism with said axis, said guide pins being shiftable, responsive to sliding movement of the guide plate, toward and away from the wheel to operative and inoperative positions respectively and being arranged, when shifted toward the wheel, for guiding of an article to be coated into engagement with said periphery, thereby to effect rotation of the wheel and coating of the article responsive to movement of said article in the direction of its length while in the wheel engaging position thereof.

circumferentially of the wheel in parallelism with said axis, said guide pins being shiftable, responsive to sliding movement of the guide plate, toward and away from the wheel to operative and inoperative positions respectively and being arranged, when shifted toward the wheel, for guiding of an article to be coated into engagement with said periphery, thereby to effect rotation of the wheel and coating of the article responsive to movement of said article in the direction of its length while in the wheel engaging position thereof.

3. A device for coating an adhesive substance upon tape-like articles, comprising: a reservoir adapted to hold an adhesive substance and shaped as a handle; a valve block secured to one end of the reservoir; a valve rotatably mounted in said block for movement to open and closed positions respectively; a well secured to the valve block and communicating with the reservoir in the open valve position, for flow of said substance between the well and reservoir; a wheel support assembly removably mounted in said well and including fixedly connected spaced side plates; a gauge plate arranged transversely of and supported on said wheel assembly; a valve handle secured to the valve for rotating the same and engaging said gauge plate in the open valve position, to hold said assembly against removal from the well, said valve handle in the closed valve position freeing said assembly for removal thereof from the well; an applicator wheel rotatably mounted on and between the side plates in position to be partially immersed in said substance, for coating of the periphery of the wheel with said substance responsive to rotation of the wheel; a guide plate disposed adjacent one face of the wheel and supported on one of the side plates for sliding movement in a plane normal to the axis of rotation of the wheel; a spring held under compression between the guide plate and said one side plate and tensioned to normally urge the guide plate away from said axis; a control handle pivotally connected to said one side plate and operatively connected with the guide plate to shift the same toward said axis against the pressure of the spring; and guide pins affixed to the guide plate in close proximity to the wheel and spaced circumferentially of the wheel in parallelism with said axis, said guide pins being shiftable, responsive to sliding movement of the guide plate, toward and away from the wheel to operative and inoperative positions respectively and being arranged, when shifted toward the wheel, for guiding of an article to be coated into engagement with said periphery, thereby to effect rotation of the wheel and coating of the article responsive to movement of said article in the direction of its length while in the wheel engaging position thereof.

ELMER A. HILLARD.
